FENDER ROLLER

Filed Nov. 13, 1928

UNITED STATES PATENT OFFICE

ALLEN PRESTON ASHER, OF SANDPOINT, IDAHO

FENDER ROLLER

Application filed November 13, 1928. Serial No. 319,081.

This invention relates to tools used for rolling out indentations or deformations in fenders or other sheet metal articles of this general character and particularly to tools 5 of this type such as are used in garages and which embody two jaws with rollers at the ends and means for tightening the jaws so as to bring the rollers in approximate contact with the fender to thereby roll out indentations or deformations.

One of the objects of the present invention is to provide a fender roller which is adapted to be mounted upon and used in connection with a spoke tightener of the character illustrated, described and claimed in Patent No. 1,669,899, granted May 15, 1928. The spoke tightener illustrated in this patent comprises a body formed with two jaws adapted to be disposed to embrace or partially embrace a 20 tire rim and having a screw-threaded shank passing through one of the jaws and engageable with the rim to press it down around the end of the spoke, the body being provided with a handle.

Another object of the invention is to so construct the fender roller that the two jaws may be detachably engaged with the handle of the spoke tightener body and extend over and parallel to the jaws above and below the 30 same respectively, said jaws being provided with rollers at their ends and provide means whereby the screw of the spoke tightener may be used for shifting one of said roller carrying jaws toward the other roller carrying jaw.

A further object of the invention is to provide means for adjusting the other roller carrying jaw so as to dispose the roller carried thereby either slightly ahead or slightly 40 behind the roller carried by the other jaw or dispose the two rollers in approximate alinement and provide means whereby the upper roller may be set ahead of the lower roller and then the lower roller set ahead of the upper roller and thus give a crown to the metal worked on.

Other objects will appear in the course of the following description.

My invention is illustrated in the accompanying drawings, wherein:—

Figure 1 is a side elevation of a fender roller constructed in accordance with my invention;

Figure 2 is a section on the line 2—2 of Figure 1;

Figure 3 is a fragmentary top plan view of the under arm and roller;

Figure 4 is a fragmentary elevation of the rear end of the lower arm;

Figure 5 is an elevation of the rear end of the upper arm.

Referring to these drawings, 10 designates the body of the spoke tightener previously referred to as forming the subject-matter of Patent No. 1,669,899. This body 10 is provided with the upper jaw 11 and the lower jaw 12, this lower jaw being bifurcated at 13. The body 10 is provided at its rear with the handle 14.

Extending through the upper jaw 11 on the body is the pressure screw 15 having a head 16 whereby the screw may be turned. The inner end of the screw is formed to carry a cap of the character set forth in detail in the patent above referred to but which it is not necessary to detail in the present application, this cap merely being used for the purpose of tightening the rim and spoke of a wheel. So far I have described the construction which is illustrated in said patent.

In carrying out my present invention, I provide the upper resilient arm 17. This arm extends parallel to the jaw 11 but in spaced relation to the same except at the rear end where the arm is bent downward at 18 and forked as at 19 so as to embrace the body 10 and seat thereon. The arm 17 is formed with an aperture through which the screw 15 passes so that as this screw 17 is turned downward, the arm 17 will be forced down. The upper arm 17 should be so formed as not to touch the top of the body 10 between the handle 14 and the power screw 15.

The lower arm 20 which is also made of resilient metal, at its rear end conforms to and extends along the under face of the body 10 as at 21 and is formed with a hook-shaped portion 22 to engage around the handle 14 at the lower end thereof. Passing through the arm 20 is a T-bolt 23 carrying the nut 24,

this bolt being disposed through the slot 13 and the cross bar of the bolt resting upon the upper face of the lower jaw 12 in the manner shown in Figure 2.

5 The arm 17 carries a roller 25 and the arm 20 a roller 26. The roller on the lower arm should be larger than the roller on the upper arm and ordinarily the lower roller 26 should be about one-half inch or so closer to the body 10 than is the upper roller 25.

10 These rollers are transversely convex as shown in Figure 3. It is to be particularly noted that the lower jaw 12 of the tightener 10 is curved upward at its forward end on its under surface and that the lower arm 20 while it conforms to the contour of the under face of the lower jaw 12 extends straight outward and upward from this lower jaw at a point about two inches from the bolt 23, 20 thus permitting the lower arm 20 to be adjusted upward by the nut 24 or by releasing the nut to permit this lower arm 20 to move downward under its own resilience.

25 The bolt 23 holding the lower arm determines the position of the rollers with relation to each other. When this bolt 23 is tightened, it raises the lower roller and shifts this lower roller nearer to the body 10 than the upper roller. When, however, the bolt is 30 loosened, the rollers will be shifted to a position directly opposite each other and if loosened further the lower roller will be shifted out beyond the other. Of course, these two rollers are relatively adjusted by the 35 screw 15 and bolt 23 until they are brought into such approximate contact with the work as will cause any indentation or deformation to be flattened out by reciprocating the rollers 25 and 26 over the work.

40 The use of the device will be obvious. The arms are opened and disposed on each side of the work. The bolt 23 is then adjusted so as to properly adjust the roller 26 with relation to the roller 25 for the work to be done and 45 then the power screw 15 is rotated to bring the rollers into a greater or less contact with the work. The operator then reciprocates these rollers over the work by means of the handle 14 until the indentation or deformation 50 has been "ironed out".

Assuming that the rollers are in position on the outer edge of a crowned fender and it is intended to force the tool inward across the crown of the fender, then as the rollers 55 are climbing to the top of the crown, the body of the tool is kept as low as possible to start with and gradually raised as the top is reached so that when the rollers are at the top of the crown, the tool is approximately 60 horizontal. As the rollers go down on the descending surface of the crown, the tool is raised gradually so that when the innermost edge is reached, the tool is elevated fully.

65 It has been found in practice that if the

rollers are adjusted so that they are directly opposite each other, the tendency is to flatten out the crown surface and they do not afford any opportunity to stretch dents out of the metal, but by setting the upper roller ahead 70 of the lower roller and then setting the lower roller ahead of the upper roller, a crown or reverse curve will be given to the metal worked on, which has been found to be particularly effective. It will be seen that the 75 arms are relatively long so that relatively deep work may be operated on and it will also be seen that the device is extremely simple and cheaply constructed as well as easily operated.

80 I claim:

1. A fender tool of the character described, comprising a body formed with upper and lower jaws and a rear handle, a power screw passing through the upper jaw and having a head, a resilient arm operatively engaged at its rear end with the body and extending over the upper jaw in spaced relation thereto and through which said power screw passes, the arm carrying a roller, a lower arm engaged at its rear end with the body and carrying a roller at its free end, the arm conforming for a portion of its length to the under face of the body, and a bolt passing through the under jaw and through said lower arm, the bolt when tightened acting to urge the lower arm upward against the jaw and when released acting to permit the lower arm to shift away from the jaw.

2. A fender tool of the character described, comprising a body having upper and lower jaws and carrying a handle, a power screw passing through the upper jaw and having a head, the lower jaw being bifurcated, an upper resilient arm engaged at its rear end with the body and extending over the upper jaw in spaced relation thereto, the power screw passing through said arm and the head bearing thereagainst, a lower arm formed at its rear end for engagement with a handle of the body and extending beneath the lower jaw, and a bolt passing through the perforated portion of the lower jaw and through the lower arm and having a nut bearing thereagainst, the upper and lower arms having rollers, one of the rollers being smaller than the other.

3. A fender tool attachment for a spoke tightener, comprising a body having an upper arm of resilient material formed at its rear end to provide two body embracing flanges and having an aperture for the passage of a power screw forward of its rear end, the forward end of the arm being provided with a roller and a lower arm of resilient material adapted to be disposed below the lower jaw of the spoke tightener body having a hook at its rear end to engage with the handle of the tightener body and having a bolt passing through the arm formed with

a cross bar for engagement with the lower jaw of the tightener, the free end of the arm having a roller.

4. A fender tool of the character described, comprising a body having upper and lower jaws, resilient arms operatively engaged with the body respectively above and below the jaws thereof and carrying rollers at their free ends, and means operatively engaging the arms and jaws whereby the arms may be adjusted toward or from each other and the rollers shifted longitudinally of the body and relative to each other to position one roller in advance of, in registry with, or behind the other roller.

5. A fender tool of the character described comprising a body having upper and lower jaws, the lower surface of the lower jaws of the body extending upward and forward, resilient arms operatively engaged with the body respectively above and below the jaws thereof and carrying rollers at their free ends, the lower arm normally extending upward at an angle relative to the upper arm, means engaging the upper arm whereby the arm may be adjusted toward or from the lower arm, and means engaging the lower arm and the lower jaw whereby said arm may be shifted toward or from the lower jaw to thereby position the roller on the lower arm in advance of, behind or opposite the roller on the upper arm.

In testimony whereof I hereunto affix my signature.

35 ALLEN PRESTON ASHER.
